UNITED STATES PATENT OFFICE

HENRY YERKEY, OF GALESBURG, ILLINOIS

SHEARS GRINDER

Application filed July 5, 1929. Serial No. 375,997.

The present invention pertains to a grinder for shears and more particularly to one which automatically feeds the blade across the grinding element as the grinding is accomplished. It has heretofore been proposed to operate by means of a motor a grinding wheel against which a shears or scissors blade is held and to manually advance the blade across the grinding wheel. My invention does not pertain to such a construction, but to one in which there is such connection between the grinding wheel and the carriage for the blade to be sharpened that the two work together in unison, always producing the desired results. Among the objects of this invention are to provide a grinding tool of the character indicated in which the functioning of the grinding wheel and of the blade carrying carriage will be coordinated so as to produce the results desired; to provide a machine of the character indicated in which the grinding wheel will produce serrations in the edge of the shear blade and the blade can be run a second time across the grinding wheel without destroying the serrations made the first time the blade traveled across the wheel; to provide in a structure of the character indicated an adjustable stop by means of which the starting position of the blade with reference to the grinding wheel may be accurately predetermined; to provide, in a machine of the character indicated, means for holding the shears blade away from the grinding wheel until the point has been reached at which it is desired to have the grinding operation commenced; to provide, in a machine of the general nature indicated, means for holding the shears blade and permitting the same to be automatically engaged with the grinding wheel as soon as the proper point therefor has been reached; to provide mechanism in a machine of the character described such that a helical groove can be cut in the grinding face of a grinding wheel and the cutting action can be repeated without destroying previously formed grooves; to provide in a structure for the purpose indicated novel means for forming a helical groove on the grinding

face of the grinding wheel; to provide in a structure of the character indicated novel means for permitting the shears carried to be moved backwardly towards the grinding element; and such further objects, advantages and capabilities as will hereafter appear and as are inherent in the construction disclosed herein. My invention further resides in the combination, construction and arrangement of parts illustrated in the accompanying drawings and, while I have shown therein what is now considered the preferred embodiment of my invention, I desire this disclosure to be understood as illustrative only and not in a limiting sense.

In the drawings annexed hereto and forming a part hereof, Fig. 1 is an elevation with a portion broken away, the same showing my improved shears grinder; Fig. 2 is a plan view of the construction shown in Fig. 1; Fig. 3 is a transverse section taken substantially along the plane indicated by the line 3-3, Fig. 1; Fig. 4 is a fragmentary vertical section substantially along the plane indicated by the line 4-4, Fig. 3, showing a detail of construction of the clutching mechanism; Fig. 5 is a fragmentary vertical section taken substantially along the plane of the line 5-5, Fig. 1; Fig. 6 is a horizontal section taken substantially along the plane indicated by the line 6-6, Fig. 3; Fig. 7 is a fragmentary view of what is now considered the preferred form of my invention; Fig. 8 is a cross-section of this construction substantially along the plane indicated by the line 8-8, Fig. 7; Fig. 9 is a fragmentary detail plan of a portion of the structure shown in Figs. 7 and 8; Fig. 10 is another fragmentary detail of this construction.

Referring now more in detail to the annexed drawings, the frame is denoted by the numeral 1 and is shown as mounted upon a base 2 and secured thereon by suitable means such as bolts 3. The frame is shown as comprising a body and a plurality of legs. Mounted in and extending longitudinally of the frame are guide rods 4 on which is carried the carriage 5. Between the guide rods 4 is shown a screw 6 which is journaled at its two ends in bushings 7, the latter being

held in place in the framework by means of the nuts 8.

Mounted upon the base 2 and within the outlines of the frame 1 is a motor 9 upon the rotary shaft of which is a belt wheel 10. Passing over this belt wheel and cooperating with belt wheel 12 is a belt 11 by means of which rotary motion is transmitted from the motor 9 to the drive shaft which carries the pulley 12. Mounted upon one end of the shaft 13 are pulleys 14 and 15 and upon the opposite end is a grinding wheel 16. This latter is preferably detachably connected to the shaft so that it may be removed and replaced by another grinding wheel having a different character of face or a different texture. Upright members 17 and 18 form a part of the frame 1 and are perforated to receive and support the shaft 13. This shaft may be mounted directly in these perforations or there may be bushings therein surrounding the shaft and forming bearings therefor. Mounted upon the shaft 6, opposite the pulleys 14 and 15 are pulleys 19 and 20. These pulleys form a speed change mechanism whereby a change can be made in the relative rates of rotation of the shafts 6 and 13, merely by shifting the belt 21 from one pair of pulleys to the other or, if the pulleys are not of such relative sizes that the same belt can be used, then by substituting for the belt in use a different belt of appropriate length. By substituting different pulleys for the pulley 15 and belts of appropriate length, various speed relations between the driving and driven shafts may be secured.

As indicated above, a block 5 is perforated and mounted upon the guide rods 4 for sliding motion with relation thereto. This block is also perforated transversely of the direction of the rods 4 and 6 for the reception of the rotary rod 22 provided with the crank arm 23. This rod is notched in one side to form a cam by means of which the block 24 may be actuated. As shown in Figs 3 and 4 this block is perforated for the reception of the rod 22 and will be actuated downwardly by rotation of said rod. A spring 25 surrounds the body of the block 24 and the two are received within a cavity 26 in the upper part of the block 5.

It will therefore be apparent that rotation of the rod 22 will cause the head 27 of the block 24 to be drawn downwardly and compress the spring 25. It is obvious that when the rod 22 is again rotated to the position shown in Fig. 3 the spring 25 will be permitted to force the block 24 upwardly again. This block has a semi-cylindrical opening in its upper face in which are cut threads, these latter being capable of engaging the threads of the rod 6. Therefore, when this rod is rotated with the threads of the block 24 in engagement therewith, the block 5 will be

caused to move longitudinally of the frame 1.

Extending outwardly from one side of the block 5 is an arm 28 which supports a carrier member comprising a base 29, a pedestal 30 and a clamping head 31. As shown more clearly in Fig. 1, the arm 28 and base 29 have a slidable interfitting undercut connection so that the base can be adjusted longitudinally of the support. The base is provided with a downwardly extending flange 32 which is perforated for the reception of an adjusting screw 33. This adjusting screw extends through a perforated and screw threaded portion 34 of the base, thereby making it possible to secure the desired adjustment between the base and supports and consequently between the holding clamp 31 and the grinding wheel 16.

The pedestal 30 is provided with a head 35 which is outwardly cylindrical and is received within a cap 36. The coil spring 37 has one end connected to the head 35 of the pedestal so that it cannot rotate relatively thereto. The opposite end of the spring extends out through a hole 38 in the wall of the cap 36. Therefore, when the holding clamp 31 which is connected with the cap 36 is rotated to place a tension upon the spring 37, the spring will have a normal tendency to rotate the cup and clamp in the opposite direction. The clamp 31 is provided with a substantially cylindrical head 39 which is perforated for the reception of a portion of a clamping device 39a. This is screw-threaded so that rotation of the nut 40 by means of the handle 41 will cause the clamp to be tightened up and hold the clamping means 31 in adjusted position. The clamping means 31 has a body 42 and a movable jaw 43, these two being drawn together by means of an adjustable screw 44. The body 42 is perforated for the reception of a holding member 45 which is hook shaped at one end and, at its other end, has connection with a nut 46. As shown in Fig. 2, this serves to clamp the handle of the shears at one point. Another part of the shears is held between the clamping jaw 43 and the projection 47 at one corner of the holding means 31, as shown in Fig. 2. When the shears has been properly inserted between the projection 47 and the clamping block 43 and the clamping screw 44 has been tightened up to hold same in adjusted position, the hook 45 is turned down in front of the handle of the shears and then the member 46 is tightened up until the handle is rigidly held. This then holds the shears tightly in properly adjusted position.

A lug 50 formed on the side of the frame 1 is perforated in a direction substantially parallel to the axis of the frame and the perforation is screw threaded for the reception of the screw 51. By adjusting the position

of this screw, the same will serve as means for accurately adjusting the stopping point of the shears carrier in its motion toward the grinding wheel. A diamond is mounted 5 in the end of the projection 47 and serves as a means for cutting the helical groove in the edge of the grinding wheel 16. Brackets 52 and 53 are mounted on the uprights 17 and 18 and are perforated for the reception 10 of the screw 54. The perforations in these brackets serve as bearings for this screw and the latter is held accurately positioned thereby. A gage 55 is perforated and has screw threaded connection with the screw 54. 15 Through one end of this bracket extends an adjusting screw 56, the opposite end 57 serving as a gage to hold the shears blade away from the grinding wheel until such time as it is desired to have the blade contact the 20 wheel. Resilient means 58 secured to the gage element bears against the casing 59 which encloses the space between the uprights 17 and 18 and the frame 1. The screw 25 56, mentioned above, also bears against the casing 59 and serves to adjust the position of the gage and thus the position of the shears blade with reference to the grinding wheel. Therefore, the blade can be held by the gage just out of contact with the grinding wheel 30 until the motor has had time to speed up. The end of the blade will then slide off the part 57 of the gage and will be forced into contact with the grinding wheel by the spring 37 which rotates the head and clamping member 31 to cause the blade to be held 35 in contact with the grinding wheel.

A switch 60 serves to make and break the circuit to the motor and the operation thereof may therefore be controlled by this 40 switch. The shaft 6 has an unthreaded portion 61 adjacent one end so that the block 5 can not be run against the end of the frame and thus, possibly, result in the breakage of the machine. Attention should perhaps be 45 called to the fact that the motor shaft and the screw 6 are shielded from the metal and mineral chips resulting from the grinding operation by reason of the fact that they are located below the body of the frame and 50 within the outline thereof.

In the construction shown in Figs. 7 to 10 there are certain respects in which it differs 55 from the structure shown in the other figures. For example, parts 50 to 58 are omitted from this structure. Also the parts supported by the base 29 are somewhat modified. In this construction the helical spring 37 is mounted in a hollow in the base 29 and has one end secured to the base and its other 60 end secured to the end of shaft 63 which extends through an opening formed lengthwise of the post 30. It will therefore be seen that, if shaft 63 is turned to put a tension on spring 37, the tendency of the spring 65 will be to return the shaft to its starting

place. A cap 64, corresponding to cap 36, is rigidly secured to shaft 63 by suitable means, such as set screw 65. The cap and shaft therefore rotate together. This cap, like the cap 36, carries the head 39. Carried 70 by this head is the shears holding frame 31a, comprising the arms 66 and 67 and the U-frame 68 to which is secured the bracket 69. Threaded in this bracket is an adjusting screw 70 which abuts against the pin 71 connecting the arms 66 and 67. The U-frame 68 is pivotally connected to these arms by the pin 72 and may be turned about this pivot to clamp a shears blade in place. The arms 66 and 67 and the frame 68 are notched as shown at 73 to receive the blade. The post 30, as shown in Fig. 10, is provided with an L-shaped slot 75 which extends through to the central channel in which is located the shaft 63. This shaft is provided with a 75 perforation into which extends a pin 76. This permits relative rotation of the bolts 30 and pin or shaft 63 but does not permit the latter to be pulled out of the former. When 80 it is desired to separate these two it is necessary to remove the pin 76. This pin also has another function which will be presently described. Extending lengthwise of the post 30 and along side of the opening for the shaft 63 is a cylindrical opening 77 in 85 which is mounted a plunger 78. A pin 79 extends through the L-shaped slot 75 and into the plunger 78, permitting this to have reciprocatory but non-rotary motion. A small diameter rod is connected to the plunger 78 and is extended downwardly and 90 bent into a hook 80 which engages the rod 22. This latter is provided at this point with a flat portion 81 which permits slight reciprocatory motion of the plunger 78. 105 Rotating the rod 22 by means of the crank 23 either pulls the plunger 78 downwardly or permits it to be forced upwardly by the spring 82. A plug 83, preferably having screw-threaded connection with the base 29 110 furnishes an abutment against which the lower end of the spring 82 may rest. As shown in Fig. 10, one side of the plunger 78 is provided with a notch into which pin 76 115 may enter when the plunger 78 is drawn down a proper distance. It will be seen from the foregoing that when the crank 23 is turned into a horizontal position, with the flat side 81 down so as to permit the hook 80 to rise, the plunger 78 will remain in the position shown in Fig. 10 until the head 64 is rotated to turn shaft 63 about its axis, thus getting pin 76 out of the notch in the plunger 78. When this happens, the spring 82, which is under compression, forces the 120 plunger 78 upwardly until the hook 80 strikes the flat spot on the shaft 22. This brings a round part of the plunger 78 opposite the pin 76 and this will hold the shaft 63 in rotated position. Since this carries the 125 130

head 31a, that is held in rotated position such that a shears blade held in the notch 73 will be prevented from engaging the grinding wheel. When the crank 23 is again 5 turned downwardly the notch in plunger 78 is brought into alignment with the pin 76 and that enters the notch when the shaft 63 turns under the influence of the spring 37. This brings the shears blade into contact 10 with the grinding wheel 16.

Operation

Barbers' shears, as they come from the factory, have very little if any serrations 15 on the edges of the blades. Barbers sometimes attempt to put such serrations upon one or both blades by the use of a file but this is uncertain and unsatisfactory and has resulted in various attempts to place such 20 serrations in the edges of the blades by means of grinding wheels of various shapes. These constructions have not been scientifically made and have not been as satisfactory as desired and I have therefore developed 25 the construction disclosed herein. If we assume that one of these machines has just been purchased and set up and that we are ready to place the helical groove on the grinding face of the grinding wheel 16, the 30 procedure will be as follows. The crank 23 will be turned through somewhere from 90 to 180 degrees from the position shown in Fig. 3 which will release the block 27 from the threads of the screw 6. The block 35 5 will then be shoved lengthwise until the arm 28 engages the screw 51. This will be adjusted to such a point that the diamond point in the projection 47 will be closely adjacent the grinding wheel but on the side 40 toward the upright 17. When this has been adjusted in this position, there will ordinarily be no need for again adjusting this screw 51 as the arm 28 will always come up against this screw and stop in the proper position, 45 when the machine is being set for operation. The next thing to do is to loosen the nut 40 and adjust the clamping member 31 to such a point that the diamond will point toward the face of the grinding stone or grinding 50 element but positioned so that the metal of the clamping member will not engage the grinding face when the helical groove is being cut. When this is properly adjusted, the nut 40 is again tightened up to hold 55 member 31 in properly adjusted position. The next thing to do is to turn the screw 33 until the diamond point is so positioned as to engage the grinding face of the grinding element. Ordinarily, no attempt will 60 be made to cut the groove the full depth the first time over as it is possible to bring the carriage back against the screw 51 and make the diamond point travel in the same path on the face of the grinding wheel in going 65 over same a second time.

We will now assume that the grinding wheel has been properly spaced and that we are ready to grind a pair of shears. The shears will now be mounted in the position shown in dotted outline in Fig. 2, the clamping screw 44 being tightened up to hold the shears in place and the hook 45 put over the handle and the nut 46 tightened up to hold the shears in adjusted position. The clamping head supporting means 29, 30 will 70 now be adjusted by means of the screw 33 until the spring 37 is put under sufficient tension to tightly hold the blade against the grinding wheel. This screw must not be turned too far or the shears blade will 75 swing in a decided arc which is undesirable. This blade should travel in a substantially straight line. The block 5 is now moved toward the driving end of the mechanism until the grinding wheel strikes the shears blade 80 at the point where it is desired to begin the grinding cut. This is normally near the pivot point of the shears but separated therefrom by a distance of from $\frac{1}{4}$ to $\frac{1}{2}$ an inch. With the block in this position, the screw 85 51 is adjusted until it just touches the face 29. With the parts thus adjusted, the carriage and shears can be brought back to starting position as many times as desired and the grooves and ridges of the grinding 90 wheel will always strike the same spots on the blade. Shears blades are always ground with a bevel and it will be seen that by loosening the nut 40 the clamping head can be turned about the bolt 39 until the blade is 95 adjusted for the grinding of the desired bevel.

In order to hold the blade away from the grinding wheel until the motor has gotten up speed, the shears blade is put against 100 the outer face of the portion 57 of the gage element 55. The position of this longitudinally with relation to the machine may be adjusted by turning the screw 54, as pointed out above. This adjustment is necessitated 105 by reason of the fact that shear blades are not all of the same length and it is therefore necessary to release some at one point and others at other points. This can be arranged for by the adjustment specified. 110 Normally, only one of a pair of blades will be ground with serrations, the other one being smooth ground. This is provided for by making the grinding wheels readily removable. A smooth faced wheel can then be substituted for it. The other blade will then take the place of the one which has been ground with serrations and this will be 115 ground on the smooth stone.

In this specification and the appended claims, the word "stone" has been used to designate the grinding wheel, irrespective of the material of which it is composed. It is of course immaterial whether this is made 120

70

from natural stone or is an artificial grinding wheel.

Having now described my invention, I claim:

- 5 1. Shears supporting means for use in connection with a shears grinder, said supporting means including a block movable lengthwise of the machine, said block having a supporting arm projecting laterally from the machine, a supporting base carrying a pedestal and being adjustable along the arm, a cup mounted on the upper end of the pedestal and rotatable with relation thereto in a substantially horizontal direction, a spring 10 to hold the cup tensioned in one direction, a clamp pivoted on the cup to swing in a substantially vertical plane, and means for rigidly holding a pair of shears in adjusted position in the clamp.
- 20 2. In a structure for the purpose indicated, a frame, a grinding wheel rotatably carried by the frame, supporting means mounted in the frame, a block supported on and moving along the supporting means, 25 means for continuously advancing the block along the supporting means, said block being constructed to hold a shears blade and carry the same across the grinding wheel, a gauge mounted on the frame in a position to 30 be engaged by the blade and hold the same out of contact with the grinding wheel, said gauge being adjustably positionable nearer to or farther from the wheel so as to coöperate with blades of different lengths.
- 35 3. A structure as defined by claim 2 provided with resilient means serving to swing the blade into contact with the grinding wheel and hold it there.
- 40 4. A structure as defined by claim 2 having means adjustably carried by the frame for adjustably limiting the traverse of the block in one direction.

In witness whereof, I hereunto subscribe my name to this specification.

45 HENRY YERKEY.
